[57] CLAIM

The ornamental design for a urine specimen collector, as shown and described.

DESCRIPTION

FIG. 1 is a perspective view taken from one side showing a first representation of the design with the two members of the collector detached;

FIG. 2 is a top view of said first representation of the design with the two members of the collector attached;

FIG. 3 is a side elevation of said first representation with the two members of the collector detached;

FIG. 4 is a bottom view of said first representation of the design;

FIG. 5 is an end elevation of said first representation with the two members of the collector detached;

FIG. 6 is a perspective view taken from below and from one side showing the first representation with the two members of the collector attached; and,

FIG. 7 is a transverse cross-sectional elevation taken along the line VII—VII of FIG. 2.
